(57) **CLAIM**

The ornamental design for a game board, as shown and described.

DESCRIPTION

FIG. 1 is a top left front perspective view of a game board showing my new design;

FIG. 2 is a top plan view thereof;

FIG. 3 is a bottom plan view thereof;

FIG. 4 is a right-side view thereof;

FIG. 5 is a left-side view thereof;

FIG. 6 is a front elevational view thereof; and,

FIG. 7 is a rear elevational view thereof.

The broken lines in the drawings show portions of the game board that form no part of the claimed design.

The “MAKE 4” not forming part of the claimed design is a registered trademark of the applicant, Mr. Russell Bennett.
